METHOD FOR FORMING BUILDING BLOCKS

Filed Oct. 9, 1944

UNITED STATES PATENT OFFICE

2,508,901

METHOD FOR FORMING BUILDING BLOCKS

Russell G. Bellezza, Baltimore, Md., assignor to
 Locke, Incorporated, Baltimore, Md., a corpora-
 tion of Maryland

Application October 9, 1944, Serial No. 557,852

4 Claims. (Cl. 25—156)

1

The invention relates to a method of forming building blocks, and more particularly to a method of forming the same of ceramic material.

Toward the accomplishment of this end, the principal object of the invention is to provide a method by which a building block of hollow box-like formation may be readily, easily and economically manufactured.

Another object of the invention is to provide a method of forming a building block having sufficient structural rigidity, strength or characteristics to permit the employment or use thereof in building structures, and possessing at the same time an exceedingly high thermal value so that the block serves not only as a construction unit, but as an insulating medium as well.

Other objects of the invention will appear in connection with the more detailed description of the invention appearing hereinafter when considered together with the accompanying drawings in which:

Figure 1 is a vertical side sectional view of a building block and mold therefor which embodies the present invention;

Figure 2 is a vertical transverse sectional view taken along the lines 2—2 of Figure 1 looking in the direction of the arrows;

Figure 3 is a horizontal sectional view taken along the lines 3—3 of Figure 1 looking in the direction of the arrows;

Figure 4 is a side elevational view shown partly in section of a completed building block removed from the mold;

Figure 5 is an end elevational view having a portion thereof shown in section to illustrate more completely the invention of a completed building block removed from the mold;

Figure 6 is a side elevational view of a modified form of the building block shown in Figures 1 through 5 inclusive, and being shown partially in section;

Figure 7 is an end elevational view of the modified form of a building block shown in Figure 6 and being illustrated partially in section.

Referring now to the drawings in detail, and more particularly to Figures 1 to 5 thereof, the numeral 1 indicates a portion of a mold in cross section, comprising transversely spaced side plates 2 and 2^a extending preferably for the full area or height of the mold, and having interposed therebetween angularly disposed intermediate sections or plates 3 and 3^a which have their contiguous extremities mitered as at 4 to present a completely enclosed box-like structure defining a material-receiving area or cavity 5 therebe-

2

tween. Positioned at the central portion of each intermediate section 3 and 3^a and desirably outstanding therefrom at the corners thereof is a lug 6 which extends into a correspondingly formed relief 7 in the side plate 2. Similarly spaced along the intermediate sections to be desirably positioned between the ends of the intermediate sections are a plurality of dowels 6^a accommodated by a plurality of recesses 7^a in the side plate 2^a. The lugs and dowels form an interlock between the respective plates for insuring a proper assembly thereof as well as retain them in a predetermined relation or assembly. Any clamping means (not shown) may be employed to act transversely or horizontally of the mold, urging the side plates toward one another.

The mold 1 is formed of plaster of Paris which has an interior configuration to agree with or conform to the desired conformation of the exterior of the object to be formed or, as in the instant case, a building block generally indicated by the reference character 8. An aperture or access opening 9 is provided in one of the intermediate mold sections in desirably the uppermost portion thereof through which fluid ceramic material may be introduced. The fluid ceramic material is poured into the mold until it completely fills the same and, by reason of the absorbent characteristics of the plaster of Paris, the fluid, carrier or water mixed into or forming a part of the fluid ceramic material is absorbed by the mold structure. This absorption by the mold structure, therefore, causes the ceramic material adjacent the inner defining walls of the mold structure to become hardened or solidified. It will be noted that the opening 9 is of considerable dimension so that it may form a reservoir or well to hold sufficient fluid ceramic material to be drawn from during the absorption period and thereby insure a complete filling of the interior of the mold structure.

After a predetermined period, hardening of the ceramic material will continue and progress inwardly of the mold structure so as to form a block structure such as illustrated at 8. When the walls of the building block have reached a thickness such as that illustrated in the drawings, the mold is inverted from the position shown in Figures 1 and 2 so as to permit the fluid ceramic material to be discharged or escape from the interior of the thus formed block and mold through the opening 9. This procedure, therefore, leaves the ceramic building block with side and intermediate or connecting walls 10 and 11 respectively, with a continuation of the opening

9 extending through one of the connecting walls, as indicated by the diagrammatic lines 12 in Figures 1 and 2. While the mold is in this inserted draining position, a plug 13, which may also be of plaster of Paris, is inserted into the opening 9 after the major portion or substantially all of the fluid ceramic material has been discharged from the mold. After the insertion of the plug 13, a continued draining of the interior of the mold will result in the aperture 12 being filled with fluid ceramic material to also become solidified and, as such, a part of the connecting wall for the completion thereof.

After a sufficient period of time has elapsed to permit the walls of the block 8 to harden or become self-sustaining, the mold is dismantled by first removing the securing means (not shown) and then moving the side plates transversely away from the completed building block; lifting one, the uppermost intermediate plate, vertically away from the block and finally, the latter being lifted off of the remaining intermediate section or plate. At this stage of the procedure, the hardened ceramic material formed by the aperture 12 which extends above the plane of the associated connecting wall, may be severed by means of a wire or any other cutting means. The building block is then allowed to dry to what is commonly known or termed as a bone dry state, at which time an orifice 14 is formed in the block and comprises an outer portion thereof conically shaped and an inner portion thereof cylindrically formed of a very minute or small diameter or bore. Glazing material is then applied to outer or front and rear surfaces or faces 15 of the block as well as to the defining surface of the conically shaped portion of the orifice. The block is then in condition for its final step of formation which is the firing operation. It will be noted that the side walls 10 are of slightly greater extent than the parallelogram as defined by the intermediate or connecting walls 11 so that there is formed on each side of the block a continuous or uninterrupted flange 16 which extends beyond the plane of the intermediate wall and thereby forms a cavity 17 for the reception of any type of bonding or binding material employed during the assemblage of a plurality of blocks in a wall structure.

Extending in opposite directions from transversely spaced intermediate or connecting walls are staggered studs or spuds 18 formed integral with the block. These spuds form firing feet upon which, during the firing operation of the ceramic block, the latter is adapted to rest. When glaze material is applied to the faces 15 it will be noted that if the glazing material should come into contact with a support or sagger (not shown) during the firing operation, the glaze would form a bond between the block and the sagger resulting in the completed glazed block being broken or damaged in removing the block from the sagger. By providing the firing feet or spuds, the glaze may be extended to the very limits of the faces 15 and since the spuds are of a height desirably or approximately one and one-half times the depth of the adjacent flange, the lowermost portion of the flange will be retained in an elevated position relative to the sagger and thereby avoid any adherence between the flanges or block and the sagger during the firing operation. The spuds, as indicated hereinabove, are staggered, as most clearly illustrated in Figure 3 so that they may not inter-

fere with one another during an assemblage of blocks in the formation of a wall structure.

Prior to the firing operation of the block, there is, as previously related, a particularly shaped orifice 14 formed in one of the connecting walls and having the defining surface of the conically shaped portion thereof covered with a glazing material so that, during the firing operation of the block, the air entrapped within the block will be free to escape through the orifice and, as the firing operation continues or progresses, more and more air will be driven or forced out of the hollow interior of the block until finally, at approximately the temperature of vitrification of the glazing material, a very small or minute amount of air will be present in the block. At this stage of the firing operation, the glazing material will creep or progress toward the cylindrical portion of the orifice 14 and, since this portion has been made so small as to prevent the glazing material from flowing therethrough, the latter will become solidified in approximately the position as illustrated in Figures 4 and 5, to form a seal closing the orifice into the block and causing a subatmospheric condition or high vacuum, to be created within the block. This subatmospheric condition within the block or the dead air space within each block serves as an insulating medium against the transfer of either heat or cold from one side wall to the other.

When the block is formed of porcelain clay, the high density of the block forming material will preserve the vacuum within the block for an indefinite period. If, however, the block is formed of a more porous ceramic material, air may enter through the pores thereof to the interior of the block, but even in this latter event, there is formed within the interior of the block a dead air space which functions as an insulating medium and, while not as effective as a vacuum, still possesses very high insulating qualities or thermal values.

If it is desired to use the blocks or portions thereof as a facing for a wall, the block, after being formed, may be severed on the diagrammatic line A—A of Figure 5, and the projecting portions of the connecting walls, after the block has been fired, form means for bonding the facing with a plaster or cement coating as is common in connection with the laying of tile, and need not be further described.

Referring now to Figures 6 and 7 of the drawings, wherein a modified form of the invention is illustrated, a building block 28 is shown partially in section and removed from a mold. The building block is somewhat similar to the mold described in connection with the first species of the invention and which is, except for the slight modifications hereinafter noted, employed to form the modified block. In the modified form of the invention, it will be noted that in place of the studs 18, there has been provided inclines or tapers 24 on all or at least the lowermost extremities of the flanges 22. These inclines in the present instance present firing feet 23 upon which the block rests during the firing operation of the block. When applying the glazing material to the outer surfaces 24 of the block, the material is not applied beyond or lower than approximately the position or location indicated at 25 in Figures 6 and 7, which will leave the balance of the taper or incline unglazed to thereby avoid adherence between the block and sagger.

In the present form also the outer surfaces 24 are of pyramidal form, as clearly indicated in

the drawings, which enhances the ornamental appearance of the block and, more specifically, materially increases the strength of or rigidifies the block against not only service stresses, but also the atmospheric condition existing within the block.

If desired, outer surfaces of the connecting walls of both blocks may be provided with a sanded surface, as shown at 26 in Figure 7, which is common in connection with insulators. This surface is formed by glazing the surface and, while the glazing material is in the moistened state, causing sand to engage with the surfaces to which it will adhere by reason of the adhesive qualities of the glazing material. When the block is fired, owing to the fusion to the glaze, the sand is firmly connected to the walls and forms a bond for mortar or cement by which the blocks may be connected to form a wall or ceiling structure.

It will, of course, be noted that since the block is a product of casting, any configuration may be formed on the faces 15 of the first species of the invention, and 24 of the second species, and further, that various changes and alterations may be made to the illustrated and described construction without departing from within the spirit of the present invention and the scope of the appended claims.

I claim:

1. A method of forming a hollow building block of ceramic material employing a mold of plaster of Paris or the like, having the walls conforming to the shape of the finished block and a filling opening therein, comprising filling the mold cavity with fluid ceramic material through said opening, allowing the material in contact with the walls of the mold to harden for a limited time, removing from the interior of the block the greater portion of unhardened fluid ceramic material through said opening, placing a plaster of Paris plug in said opening and causing the remaining fluid ceramic material to completely fill and harden in the opening in said block forming a continuation of said filling opening, removing the block from the mold, permitting the block so formed to dry, and finally firing said block to vitrify the same.

2. The method of forming a hollow building block of ceramic material, employing a multi-part closed mold of moisture-absorbent material having a filling opening therein, comprising filling said mold with ceramic material in fluid form, allowing the ceramic material in proximity to the walls of the mold to harden, pouring out of said opening the greater portion of the remaining fluid ceramic material, inserting in said opening a plug of moisture-absorbent material, causing the remaining fluid ceramic material to completely fill and harden in the opening in said ceramic material forming a continuation of said opening in said mold, opening the mold, removing the block from the mold, permitting the block so formed to dry, adding a glazing material to opposite side faces thereof, and finally firing the block so formed to vitrify the same.

3. The method of forming a hollow building block of ceramic material with a dead air space within the same, employing a multi-part closed

mold of plaster of Paris or the like having a filling opening, comprising filling the interior of the closed mold through said opening with fluid ceramic material, permitting the material adjacent the walls of said mold to harden to form a block having walls of substantially uniform thickness, removing through said opening the greater portion of the bulk of the unhardened ceramic material, plugging said opening and allowing the remaining unhardened ceramic material to completely close the opening in said block inserting a plaster of Paris plug in said opening, causing the remaining fluid ceramic material to completely fill and harden in the opening in said ceramic material forming a continuation of said opening in said mold removing the mold, forming an orifice in said block, permitting the block so formed to dry, applying glazing material to the opposite side walls and to the periphery of said orifice, and firing said block to vitrification whereby the glazing material fills and seals said orifice.

4. The method of forming a hollow building block of ceramic material having a vacuum created in the interior thereof, employing a multi-part closed mold of plaster of Paris or the like having a filling opening, comprising filling the closed mold through a suitable opening with fluid ceramic material, permitting the material adjacent the walls of said mold to harden to form a block having walls of substantially uniform thickness, removing through said opening the greater portion of the bulk of the unhardened ceramic material, plugging said opening and allowing the remaining unhardened ceramic material to completely close the opening in said block inserting a plaster of Paris plug in said opening, causing the remaining fluid ceramic material to completely fill and harden in the opening in said ceramic material forming a continuation of said opening in said mold removing the mold, forming an orifice in said block, permitting the block so formed to dry, applying glazed material to the opposite side walls of the block and to the defining surface of said opening, and firing said block to vitrification whereby the glazing material in said orifice fills and seals said orifice.
